PROCESS FOR REMOVING ACID COMPO- NENTS FROM ORGANIC LIQUIDS

Johan C. D. Oosterhout, Port Arthur, Tex., as-
signor to The Texas Company, New York, N. Y.,
a corporation of Delaware

No Drawing. Application August 23, 1945,
Serial No. 612,292

13 Claims. (CL 196—30)

1

This invention relates to a process for removing weakly acid-reacting organic substances from solutions in organic liquids. More particularly, the invention relates to a process for the removal of mercaptans from petroleum distillates.

It is known to remove weakly acid compounds such as mercaptans, phenols and the like from solution in an organic liquid by a procedure in which a solution of the acid substance is extracted with an alkaline solution containing a so-called "solutizer." The procedure has been proposed for the treatment of solutions of weakly acid substances in non-acid organic liquids such as liquid hydrocarbons, for example, petroleum liquids, benzene, toluene, and xylene; substituted hydrocarbons, for example, chloroethane, ethylene dichloride, trichlorethylene, carbon tetrachloride, chloropropane, chlorbutylene, chlorbenzene, and bromobenzene; and nitrogen containing compounds, for example, nitroethane, nitrobenzene, liquid aliphatic amines, and pyridine.

As solutizers a variety of compounds soluble in alkaline solutions have been suggested. Many of these compounds are aliphatic mono- or di-carboxylic acids. For example, alkaline solutions of isobutyric acid, particularly solutions of potassium isobutyrate in potassium hydroxide, have been found to be especially valuable for use in the removal of mercaptans from petroleum distillates. Although aromatic carboxylic acids have been considered for use as solutizers, the prior art shows that as a class these compounds are not suitable. Thus United States Patent No. 2,164,851 states that of the carboxylic acids possessing an aromatic ring phenyl acetic acid and its substitutes only are sufficiently soluble in strong caustic alkali solution to produce solubility enhancing effects of practical value. The alkali metal salts of phenyl acetic acid are said to be unique among even the salts of related phenyl-substituted aliphatic acids. This patent also shows that a true aromatic carboxylic acid, benzoic acid, is not suitable for use as a solutizer.

It is a principal object of the present invention to provide a novel and efficient process for the removal of weakly acid-reacting organic compounds from solution in non-acid water-insoluble organic liquids. A more specific object of the invention is to provide a process for the removal of a high percentage of mercaptans from petroleum distillates containing these acidic substances.

Other objects of the invention in part will be obvious and in part will appear hereinafter.

I have discovered, in accordance with the invention, that by extracting a solution of a weakly acid-reacting organic substance in a non-acid, water-insoluble organic liquid with an alkaline reacting solution containing a soluble salt of an

alkylated derivative of the mono-nuclear aromatic carboxylic acids of the benzene series a high percentage of the acidic substance is removed from the liquid. For particular application to the removal of mercaptans from petroleum distillates the salts of alkylated mono-nuclear aromatic carboxylic acids containing from 1 to 8 carbon atoms in the alkyl radical and in which the alkyl radical contains at least one tertiary carbon atom, as in the branched chain alkyl radicals, are preferred. The compounds of this class include the toluic acids, the isopropyl benzoic acids, the hydroxy isopropyl benzoic acids, the alkylated benzoic acids, such as the benzoic acids alkylated with isobutylene and di-isobutylene, and derivatives of such acids which contain substituents which do not alter the characteristic properties of the acids, particularly hydroxy, amino and like substituents.

Thus, I have found that cumic acid, p-isopropyl benzoic acid, in the form of its alkali metal salts is remarkably effective in enhancing the capacity of aqueous alkaline solutions for removing mercaptans from solution in petroleum distillates. The effectiveness of cumic acid in increasing the solubility of mercaptans in aqueous alkaline solutions does not appear to be explainable on the basis of relative solubility in caustic alkalis, since cumic acid salts are only slightly more soluble in alkaline solutions than corresponding salts of benzoic acid, which are substantially ineffective.

In carrying out the present process the organic liquid to be treated is mixed with an alkaline solution of a strong base containing the carboxylic acid in the form of a salt of the alkaline element or radical. While present experience indicates that solutions of sodium hydroxide and potassium hydroxide are superior to other alkaline solutions and are preferably used in the process, the invention includes the use of solutions of such strong bases as alkaline earth hydroxides, quaternary ammonium bases, alkali metal carbonates and bicarbonates, and the like.

Depending upon the extent of mercaptan removal desired, the extraction may be carried out in one stage or several stages. The organic liquid and the alkaline solution may simply be mixed and then allowed to settle into two layers which are then separated, or the organic liquid may be passed through a tower provided with means for accomplishing adequate mixing, such as glass beads or Raschig rings, containing the alkaline solution. When operating in this way the passage of organic liquid through the tower is continued until the percentage removal of mercaptans falls to an undesirable level. The process may be carried out effectively at room temperatures and these temperatures are gener-

ally preferred. However, higher temperatures may be used if desired.

In order to determine the relative effectiveness of cumic acid as compared with isobutyric acid and benzoic acid, a cracked naphtha distillate containing 0.1152 gram per liter of mercaptan sulphur was treated at room temperature with 20 per cent by volume of the following solutions:

- (a) An aqueous solution 2.8 N with respect to potassium hydroxide and 1.7 N with respect to potassium cumate;
- (b) An aqueous solution 5 N with respect to potassium hydroxide and 3 N with respect to potassium isobutyrate; and
- (c) An aqueous solution 1.86 N with respect to potassium hydroxide and 1.13 N with respect to potassium benzoate.

In making up solutions *a* and *c*, the potassium hydroxide and the potassium carboxylate were first combined in the proportions which would correspond to a 5 N solution of potassium hydroxide and a 3 N solution of potassium salt upon the addition of the correct amount of water. It was found, however, that in order to dissolve the potassium salts it was necessary to add water in proportions to give aqueous solutions of the concentrations indicated.

Each of these three solutions was mixed intimately with cracked naphtha distillate, the resulting mixture was allowed to settle and the distillate was then separated and tested for mercaptan sulfur content. It was found that the distillate treated with solution *a* contained only a trace of mercaptans, corresponding to more than 99 per cent complete removal of mercaptans; the distillate treated with solution *b* containing 0.0144 gram per liter of mercaptan sulfur, corresponding to an 87.4 per cent removal of mercaptans; and the distillate treated with solution *c* containing 0.0384 gram per liter of mercaptan sulfur, corresponding to 66.6 per cent removal of mercaptans. The amount of mercaptans removed by the use of solution *c*, containing potassium benzoate, was about the same as could be removed by means of a strong caustic wash.

Two other treatments were carried out in a similar manner for removing mercaptans from a cracked naphtha distillate containing 0.0576 gram per liter of mercaptan sulfur. One sample of the distillate was treated at room temperature with 15 per cent by volume of a 2.9 N aqueous solution of potassium hydroxide, and the other sample was treated with an aqueous solution 2.8 N with respect to potassium hydroxide and 1.7 N with respect to potassium cumate. After the treatment, the first sample was found to contain 0.0208 gram per liter of mercaptan sulfur, corresponding to about a 63.8 per cent removal of mercaptans, while the second sample gave a negative doctor test indicating substantially zero mercaptan content.

Although the above results show that aqueous solutions of potassium hydroxide and potassium cumate containing less potassium hydroxide than has previously been considered most desirable are entirely suitable, it will be understood that stronger solutions may be used if desired.

Additional tests have been conducted to determine the effectiveness of sodium cumate with varying concentrations of sodium hydroxide and potassium cumate in lower concentrations of potassium hydroxide. The following results were obtained in the extraction of synthetic solutions

of mercaptans in cleaners naphtha. Solutions of propyl, butyl and amyl mercaptan were prepared containing 3.8 grams of propyl mercaptan per liter, 4.5 grams of butyl mercaptan per liter, and 1.04 grams of amyl mercaptan per liter. These solutions were then treated at room temperature with 20% by volume of the extractant solution, by mixing intimately and allowing to settle, after which the naphtha was separated and tested for mercaptan sulfur content by titration with silver nitrate. In those experiments in which the total mercaptan sulfur content was not removed the naphtha solution was again subjected to the foregoing treatment and quantitative determinations of the amount of sulfur removed in the second extraction were made.

20	Extractant	Mercaptan Concentration in Naphtha

35 It has been found that the treating solutions of the present invention can be regenerated satisfactorily by known methods. For example, a solution of potassium cumate in aqueous potassium hydroxide has been regenerated successfully simply by boiling the solution while adding water to maintain a constant volume. Other methods of regeneration, such as a method involving blowing steam through the spent solution, can be used.

40 It will be understood that the present process is not limited to the use of substantially pure carboxylic acids of the class described. For example, a caustic solution comprising an alkali metal salt of cumic acid may be prepared by oxidizing crude or relatively pure isopropyl toluene in known manner, for example, by blowing with air in the presence of lead oxide, removing the catalyst, as by treating with an acid where a catalyst such as lead oxide has been used, and then washing the oxidized material with a caustic solution to form a resulting caustic solution containing an alkali metal salt of cumic acid. The invention includes the use of solutions prepared in this way and by similar methods. The isopropyl toluene used in this method may be produced by alkylating toluene derived from cracked naphtha or straight run gasoline, with propylene, or by alkylating a 200° to 260° F. 45 naphtha or gasoline cut with propylene, for example, under conditions similar to those used in the manufacture of cumene.

50 The process of the invention is entirely satisfactory when carried out with the use of alkaline solutions containing only one of the carboxylic acid salts. However, if desired, the solutions may also contain a hydroxy aromatic compound soluble in the alkaline solution, especially alkyl phenols in the form of their alkali metal salts.

This application is a continuation-in-part of my copending application Serial No. 485,092, filed April 29, 1943, now abandoned.

Obviously many modifications and variations of the invention, as hereinbefore set forth, may be made without departing from the spirit and scope thereof and therefore only such limitations should be imposed as are indicated in the appended claims.

I claim:

1. The process of separating weakly acid-reacting compounds from a non-acid water-insoluble organic liquid in which they are dissolved and which is substantially inert toward caustic alkali under the conditions of the process, comprising extracting said water-insoluble organic liquid with an aqueous alkaline solution of a salt of an alkyl substituted mono-nuclear aromatic mono-carboxylic acid of the benzene series, under conditions to absorb at least a portion of said weakly acid-reacting compounds in the aqueous solution.

2. The process of separating mercaptans from a hydrocarbon liquid in which they are dissolved, comprising extracting said hydrocarbon liquid with an aqueous alkaline solution of a salt of an alkyl substituted mono-nuclear aromatic mono-carboxylic acid containing from 1 to 8 carbon atoms in the alkyl radicals thereof, under such conditions that at least a portion of said mercaptans is extracted into the aqueous solution.

3. The process of separating mercaptans from a hydrocarbon liquid in which they are dissolved, comprising extracting said hydrocarbon liquid with an aqueous alkaline solution of a salt of an alkyl substituted mono-nuclear aromatic mono-carboxylic acid in which the alkyl substituents contain at least one branched chain alkyl group and from 1 to 8 carbon atoms, under such conditions that at least a portion of said mercaptans is extracted into the aqueous solution.

4. The process of separating weakly acid-reacting compounds from a non-acid water-insoluble organic liquid in which they are dissolved and which is substantially inert toward caustic alkali under the conditions of the process, comprising extracting said water-insoluble organic liquid with an aqueous alkaline solution of an isopropyl substituted mono-nuclear aromatic mono-carboxylic acid, under such conditions that at least a portion of said weakly acid-reacting compounds is extracted into the aqueous solution.

5. The process of separating weakly acid-reacting compounds from a non-acid water-insoluble organic liquid in which they are dissolved and which is substantially inert toward caustic alkali under the conditions of the process, comprising extracting said water-insoluble organic liquid with an aqueous alkaline solution of a hydroxy isopropyl substituted mono-nuclear aromatic mono-carboxylic acid, under such conditions that at least a portion of said weakly acid-reacting compounds is extracted into the aqueous solution.

6. The process of separating mercaptans from a hydrocarbon liquid in which they are dissolved, comprising extracting said hydrocarbon liquid with an aqueous alkaline solution of an alkali metal salt of an isopropyl substituted mono-nuclear aromatic mono-carboxylic acid, under conditions to absorb at least a portion of said mercaptans in the aqueous solution.

7. The process of separating mercaptans from a hydrocarbon liquid in which they are dissolved, comprising extracting said hydrocarbon liquid with an aqueous solution of an alkali metal hydroxide containing an alkali metal salt of an alkyl substituted mono-nuclear aromatic mono-carboxylic acid, under conditions to absorb at least a portion of said mercaptans in the aqueous solution.

8. The process of separating mercaptans from a hydrocarbon liquid in which they are dissolved, comprising extracting said hydrocarbon liquid with an aqueous solution of an alkali metal hydroxide containing an alkali metal salt of an isopropyl substituted mono-nuclear aromatic mono-carboxylic acid, under conditions to absorb at least a portion of said mercaptans in the aqueous solution.

9. The process of separating weakly acid-reacting compounds from a non-acid water-insoluble organic liquid in which they are dissolved and which is substantially inert to caustic alkali under the conditions of the process, comprising extracting said water-insoluble organic liquid with an aqueous solution of a strong base containing in solution a salt of cumic acid, under conditions to absorb at least a portion of said weakly acid-reacting compounds in the aqueous solution.

10. The process of separating mercaptans from a hydrocarbon liquid in which they are dissolved, comprising extracting said hydrocarbon liquid with an aqueous solution of an alkali metal hydroxide containing an alkali metal salt of cumic acid, under conditions to absorb at least a portion of said mercaptans in the aqueous solution.

11. In the process of separating mercaptans from a hydrocarbon liquid in which they are dissolved, involving extracting said hydrocarbon liquid with an aqueous solution of a strong base to remove mercaptans from said hydrocarbon liquid, the improvement which comprises incorporating in the said aqueous solution an alkali metal salt of cumic acid.

12. The process of separating mercaptans from a sour petroleum distillate which comprises extracting said distillate with an aqueous solution of potassium hydroxide containing potassium cumate in solution, to form an aqueous layer comprising said aqueous solution and absorbed mercaptans and a hydrocarbon layer consisting essentially of treated petroleum distillate, and separating said layers.

13. The process of separating weakly acid-reacting compounds from a hydrocarbon liquid in which they are dissolved, comprising extracting said hydrocarbon liquid with an aqueous solution of a strong base containing in solution a salt of cumic acid, under conditions to absorb at least a portion of said weakly acid-reacting compounds in the aqueous solution.
